Primary Examiner — Brian N Vinson(74) *Attorney, Agent, or Firm* — Brinks, Gilson & Lione(57) **CLAIM**

The ornamental design for a dispenser for hygiene products, as shown and described.

DESCRIPTION

FIG. 1 is a top and front perspective view of a dispenser for hygiene products dispenser showing our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is bottom and rear perspective view thereof.

The broken line disclosure represents portions of the dispenser which form no part of the claimed design.
